ABSTRACT OF THE DISCLOSURE

A container has a weighted end and an open end. A cap with a greater periphery than the container is slideably fitted over the open end. Attached to the cap is a line which is interfolded with chaff contained within the container. The air drag on the falling container and cap pulls the cap free of the container, extending the rope from the container thus dispersing the enclosed chaff.

This invention relates to the packaging and dispensing of a plurality of discrete fibers of various lengths in the earth's atmosphere to reduce the effectiveness of attempts made by an enemy to detect and track aircraft and missiles and to predict the course thereof by radar.

The fibers to be dispensed may consist of vitreous material such as glass or vitreous silica, coated with a conductive metal such as aluminum, magnesium, silver or copper; or alloys containing these metals. The fibers may be of any convenient diameter; however, it has been found that fibers of 20 to 40 microns are very satisfactory. Likewise, the metal coating may be made of any convenient thickness; however, it has been found that a metal thickness of 2 to 100 microns is very satisfactory.

Each individual fiber, when floating in the atmosphere, acts as a dipole. Electromagnetic radiation of a frequency which is resonant with the dipole is reinforced by resonance in the dipole, and radiation is in effect rebroadcast by the coated fiber acting as a dipole. In effect, each dipole acts as a reflector. The radiation emanating from a plurality of dipoles, which are resonant with the frequency emitted from an enemy's radar apparatus, appears on the oscilloscopes of the enemy as a bright cloud or bright object having various characteristics depending on the manner in which the dipole material is dispensed.

Fibrous matter having a length of say $\frac{1}{4}$ inch to about $1\frac{1}{2}$ inches will be hereinafter referred to as "chaff." Fibrous matter longer than chaff, which may be up to 500 feet in length, but preferably from about 3 inches to 100 feet in length, will be hereinafter referred to as "rope." Such rope may be round, or it may be in the form of flat tapes. Such rope is not intended to be resonant with radar frequencies. It is, however, intended to respond to other frequencies, or to emit radiation in response to frequencies to which it is not resonant.

It is generally preferred to dispense a certain amount of rope and a certain amount of chaff, more or less simultaneously. This invention provides means for carrying such rope and chaff in an aircraft or missile, and dispensing it in the atmosphere from the carrying vehicle at the appropriate time.

The primary object of this invention is to provide an improved means for carrying on an airplane or missile, material to be dispensed as chaff or rope.

Another object of this invention is to provide a means for dispensing the material from its container.

A further object of this invention is to package the rope and chaff within a container in such manner that the entire packaged material will not be released instantaneously into the atmosphere.

2

Yet another object of this invention is to provide a container openable by drag through the air.

Additional objects, advantages and features of the invention reside in the construction, arrangement and combination of parts involved in the embodiment of the invention as will appear from the following description and accompanying drawings wherein:

FIG. 1 is a vertical cross section through the container and showing the method of packaging the rope and chaff therein.

FIG. 2 is a plan section along line 2—2 of FIG. 1.

FIG. 3 is a vertical section similar to FIG. 1 and showing the lid removed from the can and acting as a drag chute to withdraw the rope and chaff from the can.

Referring to the drawing, the container referred to generally as container 10 has an open end can 12 and a removable lid 14. The can, as shown on FIG. 2, may be made square, or it may be made round or any other convenient form without departing from the invention. The lid, on its underside, is provided with spring clips 16 joined to the lid for removably holding the lid in place over the open end of the can as shown on FIG. 1.

Lid 14 is of an area greater than the cross-sectional area of the can so as to laterally extend beyond the sides of the can. The lid is provided with a rim 18 about the perimeter to provide a drag lip for a purpose to be hereinafter described.

The bottom of the can 10 has an inwardly formed cavity 20 in which weight 22 is installed to provide a bottom weighted can.

Within the can, the rope and chaff is accordion packed as shown on FIG. 1. Rope 24, which may be in the form of filaments of the same material as the chaff, or which may be made in tape form as dictated by the particular application, is shown for clarity on the drawings in tape form. Rope 24, has one end 26 joined to the can and the other end 28 joined to the inner or under side of lid 14. The can is packed with the rope convolutedly folded or accordion pleated as shown, and containing chaff 30 interspersed between the folds or pleats. The chaff may be placed into the can in any convenient form, without departing from the invention. For example: it may be more or less horizontally placed, as shown on pleats A of FIG. 1, or more or less vertically placed as shown on pleats B, or it may be jumbled as shown on pleats C.

Any number of containers as described and filled with rope and chaff may be carried aloft and released at the appropriate time. As the containers are discarded from the carrier vehicle, the weighted end of the cans will go to the bottom. When sufficient velocity has been attained, drag on the underside of lid 14 and the drag lip formed by rim 18 will cause the lid to become detached from the can and act as a drag chute on the can, which continues to fall. As shown on FIG. 3, the drag chute action of the lid pulls on the rope, causing it to be pulled from the can to thereby disperse the chaff, pleat by pleat.

It is noted that, as above described, the rope was built to have electrical characteristics for purposes as described.

However, should it be desired to dispense chaff only, the rope may be made of material without electrical properties, as for example, cotton tape.

It is to be understood that the embodiment of the present invention as shown and described is to be regarded as illustrative only and that the invention is susceptible to variations, modifications and changes within the scope of the appended claims.

I claim:

1. Means for packaging and dispensing chaff into the earth's atmosphere from an aircraft or other space vehicle and comprising: a container having an open end can and a lid having an area greater than the cross-sectional

area of said can to laterally extend beyond the sides of said can, said lid being slidably joined at the underneath side to the open end of said can and having a rim about the perimeter to provide a drag lip, said lid being removable from said can during free fall in the atmosphere due to air acting on the drag lip and the dispensing means convolutely folded within said open end can and having one end joined to said can and the opposite end joined to the underside of said lid, and chaff contained within said can and interspersed in the folds of said dispensing means to be dispersed into the atmosphere as the said lid acting as a drag chute withdraws the folded dispensing means from within said can.

2. Means for packaging and dispensing chaff into the earth's atmosphere from an aircraft or other space vehicle and comprising: a container having a can with an open end and a weighted bottom on the opposite end, and a lid having an area greater than the cross-sectional area of said can to laterally extend beyond the sides of said can, said lid being slidably joined at the underneath side to the open end of said can and having a rim about the perimeter to provide a drag lip, said lid being removable from said can during free fall in the atmosphere due to air acting on the drag lip and the underside of said lid, flexible elongated dispensing means convolutely folded within said open end can and having one end joined to said can and the opposite end joined to the underside of said lid, and chaff contained within said can and interspersed in the folds of said dispensing means to be dispersed into the atmosphere as the said lid acting as a drag chute withdraws the folded dispensing means from within said can.

3. Means for packaging and dispensing chaff into the earth's atmosphere from an aircraft or other space vehicle

and comprising: a container having a can of rectangular cross section with an open end and a weighted bottom on the opposite end, and a lid having an area greater than the cross-sectional area of said can to laterally extend beyond the sides of said can and further having a plurality of springs clips on the underneath side engaging the open end of said can be releasably holding said lid to said can and having a rim about the perimeter to provide a drag lip, said lid being removable from said can during free fall in the atmosphere due to air acting on the drag lip and the underside of said lid, a flexible elongated dispensing tape within said can, said tape being convolutely folded into folds parallel to the open end of said can and having one end joined to the inside of said can with the opposite end joined to the underside of said lid, and chaff comprising a plurality of discrete fibers contained within said can and interspersed in the folds of said dispensing tape to be dispersed into the atmosphere as the said lid acting as a drag chute withdraws the folded dispensing tape from within said can.
